UNITED STATES PATENT OFFICE.

CALEB C. BURROUGHS, OF DECATUR, ILLINOIS.

BEATER FOR CORN-SHELLERS.

SPECIFICATION forming part of Letters Patent No. 233,066, dated October 12, 1880.

Application filed July 14, 1880. (No model.)

To all whom it may concern:

Be it known that I, CALEB C. BURROUGHS, of Decatur, in the county of Macon and State of Illinois, have invented certain new and useful Improvements in the Construction of Beaters for Corn-Shellers; and I do hereby declare that the following is a full, clear, and exact description thereof, reference being had to the accompanying drawings, in which—

10 Figure 1 represents a longitudinal vertical section of a corn-sheller having the improved beater. Fig. 2 represents, in transverse section and front view, one of the beaters. Fig. 3 is a perspective view of a piece of wrought-iron or steel cut, bent, and shaped for use as a tenacious metal core in forming the beater. Fig. 4 represents, in transverse section and front view, a modification of the beater.

15 My invention relates to the construction of beaters or feeders of corn-shellers.

The object of my invention is to re-enforce these pieces of a corn-sheller by means of a tenacious core of wrought-iron or steel, so that if, while revolving, the arms meet obstructions of such size or weight as to crack the cast-iron forming the bulk of said arms, the broken piece will not fly out of the sheller, endangering attendants, or pass through the shelling apparatus and screens, damaging the latter, but will remain united to the hub until a new one can be substituted.

20 Heretofore wrought-iron in the form of perforated plates or woven wires has been used within molded cast-iron safe-plates, and also 25 within the paddles of disintegrating-mills, to add strength or hardness to the cast metal, and I am aware that the principle of uniting wrought and cast iron is not new; my invention relating only to the peculiar mode of 30 uniting the arms to the hub of a corn-sheller beater.

25 My invention consists in combining with the hub and arms of a corn-sheller cast-iron beater a permanent core formed of tenacious 35 plate-metal, having its central portion split lengthwise and bent in opposite directions and its outer portions provided with notches

or indentations and projections for engagement with the fluid metal cast around it in forming said corn-sheller beaters.

50 In the corn-sheller represented in the drawings, A represents the frame; B, the main shaft, operated through the pulley C. On the shaft B is secured the trunco-conical sheller D, and the latter is surrounded by the conical casing E.

55 On the cylinder-shaft are secured beaters or feeders I, which work directly under the hopper G, as shown. These beaters or feeders prevent the corn from arching in the hopper, and prepare the corn for the conical sheller D by partially shelling and forcing the corn to the shelling-surfaces of the cone and casing.

60 It occasionally happens that blocks of wood, horseshoes, &c., are dropped with the corn into the hopper. The feeders I, while rapidly revolving, strike these bulky, heavy, or unyielding substances, and one or both arms of a beater become broken off and separated 65 from the hub, and either fly off the hopper or enter and pass between the grinding-surfaces of the sheller, causing great damage thereto and to sieves generally placed adjoining to the sheller.

70 To prevent the breaking of the arms I or their separation from the hub I' of the beater, I unite them by a central core of tenacious wrought-iron or steel. This is preferably made, as shown in Fig. 3, of a flat plate, L, 75 split lengthwise at l, forming bands l' and l'' to encircle the eye of the hub, and arms l³, provided with indentations l⁴, in which the melted cast-iron forming the main component part of the beater enters, and in cooling becomes firmly united to the tenacious internal plate.

75 Each arm of the beater may be united to the hub by a flat plate, L', independent of the other, as shown in Fig. 4. The plate, extending over the weak point of junction of the arm with the hub, is provided with indentations l⁴ adjoining each end, as a lock for the molten cast-iron. One or both of these plates

L' may be made to extend within the eye of the hub, as a key to secure the beaters to the main shaft.

Having now fully described my invention, I

5 claim—

In combination with the hub and arms of a corn-sheller cast-iron beater, the internal wrought-iron or steel plate, *L*, split lengthwise in its central position, and the parts

bent in opposite directions, having bands *l'* to and *l*², to encircle the eye of the hub, and arms *l*³, provided with indentations, substantially as and for the purpose described.

CALEB C. BURROUGHS.
